UNITED STATES PATENT OFFICE

ALEX EPSTEIN, OF BROOKLYN, NEW YORK

DESIGN FOR A KNITTED CAP OR SIMILAR ARTICLE

Application filed May 16, 1931. Serial No. 39,866. Term of patent 3½ years.

To all whom it may concern:

Be it known that ALEX EPSTEIN, citizen of the United States and resident of Brooklyn, in the county of Kings and State of New York, has invented a new, original, and ornamental Design for Knitted Cap or Similar Article, of which the following is a specification, reference being had to the accompanying drawings, forming part thereof, in which,

Fig. 1 is a perspective view of a knitted cap embodying my new design; and
Fig. 2 is a side elevational view thereof.

I claim:

The ornamental design for a knitted cap or similar article, substantially as shown.

Dated, May 14, 1931.

ALEX EPSTEIN.
